Inventor:

G. M. Bull

United States Patent Office.

GEORGE M. BULL, OF NEW BALTIMORE, NEW YORK.

Design No. 3,792, dated December 21, 1869.

DESIGN FOR A COFFEE OR TEA-FILTER.

The Schedule referred to in these Letters Patent and making part of the same.

To all whom it may concern:

Be it known that I, GEORGE M. BULL, of New Baltimore, county of Greene, and State of New York, have invented a new and original Design for Coffee and Tea-Filter; and I do hereby declare that the following is a full, clear, and exact description thereof, which will enable others skilled in the art to make and use the same, reference being had to the accompanying drawings, forming part of this specification.

My invention has for its object to furnish a new design for a coffee and tea-filter; and

It consists in the design herein shown and set forth.

A is the body of the filter, which is made cylindrical in form, and is closely perforated with fine holes, as shown in the figure.

Around the upper end of the body A, at a little distance from its edge, is formed a bead, a' , as shown.

B is the cap or cover, which fits neatly upon the upper end of the body A, and the top plate of which is made convex, as shown in the figure.

C is the bottom of the filter, which is also made convex in form, as shown in the figure.

Having thus described my invention,
I claim as new, as far as it is now perfected—

The design for a coffee-filter herein set forth and described.

The above specification of my invention signed by me, this 24th day of November, 1869.

G. M. BULL.
